PIVOTED JAW SCREW CAP REMOVER

George T. Derby, Jacksonville, Fla.

Application November 26, 1947, Serial No. 788,194

3 Claims. (Cl. 81—3.44)

1

The present invention relates to improvements in household devices, and provides an improved combined jar opener, can opener and bottle opener.

More particularly the invention relates to an improved opener for jars having screw-tops, wherein the opening means are readily adjustable, and readily lockable in adjusted position.

A further object of the invention is to provide a jar opener for screw-top jars which embodies an improved adjustable jaw construction which positively grips the jar top, and which is associated with simple clamping means for clamping the adjustable jaw in opening engagement with the jar top.

A still further object of the invention is to provide a unitary device including cooperating clamping jaws, one of which is fixed and the other is movable for gripping a screw-top jar for opening the same, coupled with means for prying up pry-off caps, and bottle opening means all actuated by the same lever bar.

A still further object of the invention is to provide an opener of the above-indicated character having a fixed jaw member and a pivotally mounted jaw member having mounting means which permits the locking of the pivotally mounted jaw in clamping position in engagement with a top to be opened that is held against the fixed jaw member, the mounting means for the pivotally mounted jaw enabling the jaw to pivot freely at all times on the mounting means for enabling self-positioning of the jaw against the top to be removed.

A still further object of the invention is to provide an opener of the above-indicated character wherein the pivotally mounted jaw is provided with top engaging surfaces adapted to center the pivotally mounted jaw responsive to the clamping engagement thereof with a top to be opened.

A still further object of this invention is to provide a jar-top remover, having a fixed jaw member and a pivotally mounted jaw member means which will secure the pivotally mounted jaw member in proper relation with the fixed jaw member when the jaws are moved into operative relation with a jar top, the said means including a stud with a locking bolt therein, and lever means integral with the bolt for shifting the stud between locking and adjusting positions.

A still further object of the invention is to provide a wrench-like screw-top remover for removing tops from jars or the like, having opposed jaws which will automatically adjust themselves to tops of different diameters when placed in en-

2

gagement therewith, together with means for locking the jaws in adjusted clamping engagement with the top.

Further objects of the invention will become apparent as the description proceeds, and the features of novelty will be pointed out in particularity in the appended claims.

The invention will be understood more readily by reference to the accompanying drawings, in which

Fig. 1 is a perspective view of the device, showing it in operative position for opening a screw-top container.

Fig. 2 is a plan view of the bottom side of the device.

Fig. 3 is a side elevation of the device.
Fig. 4 is a plan view of the locking means embodied in the construction.

Fig. 5 is an enlarged sectional elevation showing the locking means of Fig. 4 mounted in position in the device of the invention, the view showing the actuating means for the locking means and the mounting thereof on the locking means.

Referring more particularly to the drawings,
25 the device of this invention includes an elongated
lever bar 1 and which is provided with a slot 2
extending along the median line of the bar as
shown. One end of bar 1 is provided on its un-
derside with a fixed jaw 3 having gripping teeth
30 4 thereon, which project inwardly to grip the
screw-top A of a jar, container, or the like, a
movable jaw 5 co-operating with this jaw 3 to
grip the screw top (indicated at A) between itself
and the fixed jaw 3. In order to grip the top A
35 the jaw 5 includes diverging sides 6 and 7, which
diverge from the mounting 8, as will be apparent
from the drawings, said sides 6 and 7 terminate
in serrated, arcuate gripping surfaces 9 and 10,
that are adapted to grip the top A therebetween.

40 The mounting means 8 for the jaw 5 includes a stud 11 that has a narrowed end portion 12 adapted to fit into the slot 2, the length of which end portion however is greater than the width of the slot 2, and equal to the diameter of the 45 stud 11. The narrow end portion 12 defines opposite shoulders 13 and 14 with the body of the stud 11, and forms a neck for receiving the bar 1. The opposite end of the stud 11 is enlarged with a collar or flange 15, which retains the jaw 5 in place on the mounting means. The stud 11 is provided with a longitudinally extending axial, internally threaded bore 16 adapted to receive a bolt 17, which is provided with a head 18 and threads 19. The bolt head 18 is provided with a 50 lever arm 20 for turning the bolt, so that when 55

the jaw 5 has been moved along the slot 2 into clamping position with the screw top against the bar 1, turning of the lever arm 20 draws shoulders 13 and 14 and bolt head 18 into clamping engagement with the bar or handle 1 and anchoring the mounting 8 in jar top gripping position with respect to the bar or handle 1 against displacement during the movement of said bar or handle in top removing direction. The jaw 5 thus is locked in position against the screw top A on the bar 1, the jaw 5 however being freely movable with respect to the stud 11 to permit its self-adjustment with respect to the screw top A due to the configuration of the gripping surfaces of the jaw 5.

The bar 1 is recessed as shown at 21, the cut out portion being bent down to form the flange 22 which provides means for prying off lift-tops that are clamped onto a container. The bar 1 is also notched as at 23 adjacent to its end opposite to the fixed jaw 3 to provide bottle-cap removing means. Thus there is provided an all-purpose opening tool for opening any type of closure for containers whether said closures be screw-tops, bottle tops or clamped covers, the bar 1 serving as the actuating lever for each purpose.

From the above it will be apparent that I have designed a jar or container top opening device, comprising few parts, readily applicable to and easily operable, simple and sturdy in construction, manufacturable at a negligible cost, and efficient for the purposes intended.

Although in practice it has been found that the form of the invention illustrated in the accompanying drawings and referred to in the above description as the preferred embodiment is the most efficient and practical, yet realizing that conditions concurrent with the adoption of the invention will necessarily vary, it is desired to emphasize that various minor changes in details of construction, proportion and arrangement of parts, may be resorted to within the scope of the appended claims without departing from or sacrificing any of the principles of this invention.

Having thus described the invention, what I desire protected by Letters Patent is as set forth in the following claims.

I claim:

1. In an opener for jar tops and the like, the combination of a jaw-carrying member having a handle with a longitudinal slot therein and including a stationary jaw, a grip member having a cooperating jaw portion, mounting means for the grip member including a stud rotatably extending through said grip member and having a large retaining flange therefor, said stud having a narrowed portion adapted to enter the said slot and for adjustment therein, said stud having an internally threaded bore, a bolt threadedly engaging in said stud and formed with handle engaging means, and a lever arm in connection with said engaging means for effecting tightening of the mounting on said handle for preventing its longitudinal movement with respect to said slot when said stationary jaw and grip member are in jar top engaging position, said grip

member being always freely pivoted on the stud to permit its self-adjustment with respect to the jar top to be opened.

2. An opening device for jar tops and like containers, which comprises an actuating bar, a clamping jaw fixedly mounted on the bar adjacent to one end thereof, the bar being provided with an elongated median slot, an adjustable clamping jaw adapted for longitudinal adjustment relative to the bar and fixed clamping jaw, means for mounting the adjustable clamping jaw on the bar including a stud having a restricted neck portion entering the slot and defining opposite shoulders on the stud adapted to retain said bar, a retaining collar on the stud for holding the adjustable jaw, said adjustable jaw being loosely mounted on said stud, a bolt threadedly mounted in the stud, a lever arm on the bolt adapted to move the stud between free-sliding position in the slot and locked position against the bar for securing the adjustable jaw in clamping position against a screw top for clamping said top between the fixed jaw and the movable jaw, and converging arcuate top-engaging surfaces on the adjustable jaw surfaces for enabling the jaw to be self-centering against the top when moved to clamping position thereon.

3. An opening device for opening jar tops and the like, which comprises an actuating bar, a clamping jaw fixedly mounted on the bar adjacent to one end thereof, the bar being provided with an elongated substantially median slot, an adjustable clamping jaw, means for mounting said clamping jaw for relative adjustment with respect to said slot including a stud having a restricted neck portion extending into the slot and defining opposite shoulders on the stud, the said shoulders forming abutment surfaces for the bar on each side of the slot, said stud being freely rotatable through said adjustable jaw to effect pivotal mounting of said jaw, a retaining flange for securing the adjustable jaw on the stud, a bolt threadedly mounted in the stud, a head for the bolt having a diameter greater than the width of the slot for retaining the stud in the slot, a lever arm on the bolt head effecting adjustment of the adjustable jaw with respect to the slot and clamping engagement of said head and shoulders with said bar to lock the stud and adjustable jaw in predetermined position on the bar relative to the fixed jaw, and means on the adjustable jaw for centering the jaw relative to the top on a container responsive to clamping engagement of the jaw with the top.
